United States Patent Office

Des. 197,522
Patented Feb. 18, 1964

197,522

PLAYGROUND UNIT

Claude Wesley Ahrens, Grinnell, Iowa

Filed Nov. 23, 1962, Ser. No. 72,588

Term of patent 14 years

(Cl. D34—5)

Fig. 1

Fig. 2

FIG. 3

FIG. 4

FIG. 5

FIGURE 1 is a perspective view of the playground unit showing my new design;

FIGURE 2 is a side elevation view;

FIGURE 3 is a top view;

FIGURE 4 is a rear end elevation view;

FIGURE 5 is a front end elevation view;

FIGURE 6 is a perspective view of the playground unit wherein a ladder arrangement has been substituted for the top bars and the end standards are of uniform length;

FIGURE 7 is a top view of the unit shown in FIGURE 6;

FIGURE 8 is a side elevation view of the unit shown in FIGURE 6; and

FIGURE 9 is an end elevation view of the unit shown in FIGURE 6.

I claim:

The ornamental design for a playground unit, substantially as shown and described.
